Jacob D. Edwards, Elizabeth Town New Jersey
Letters Patent No. 18. dated March 20th 1844

The Schedule referred to in these Letters Patent and
making part of the same.

To all whom it may concern: Be it known that
I, Jacob D. Edwards of Elizabeth Town in the County
of Essex, and State of New Jersey, have invented, a new
design or figure to be printed or stamped on painted
cloth or canvas, or other fabric, which when thus printed or
stamped is termed "Floor Oil Cloth Carpetting", and I do
hereby declare that the following is a full and exact descrip-
tion of the same to wit. The design or drawing or figure
called "Mosaic No. 250 A" as represented in the con-
formation by the Black, White ^{dark legs or stone color} light lead or stone Col's
do in themselves represent the various parts, being of dif-
ferent forms and shapes, which by their union and arrange-
ment form a figure or design, as is represented by the
drawing or design to which reference is made; And I claim
for this invention, that when this design is printed or
stamped upon painted cloth, canvas or other fabrics it
forms a series of figures representing Separated or
Mosaic Work, in imitation of wood or stone, according
to the nature of the colours, used for printing or stamping
the same and which is usually denominated "Floor
Oil Cloth Carpetting" which in the form and config-
uration of its various figures represents an entire and original
new design for the purposes herein stated, and which I
claim as my invention and desire to secure the same
and therefore
